CLAIM

The ornamental design for a fire protection port fog nozzle, as shown and described.

DESCRIPTION

FIG. 1 is a perspective view of a fire protection port fog nozzle showing my new designs;

FIG. 2 is a front elevational view;

FIG. 3 is a side elevational view, the opposite side view being a mirror image of that shown;

FIG. 4 is a rear elevational view;

FIG. 5 is a top plan view; and

FIG. 6 is a bottom plan view.

FIG. 1

FIG. 2

FIG. 3

FIG. 4

FIG. 5

FIG. 6
